UNITED STATES PATENT OFFICE.

JOHN G. TRENEAR, OF HUNTINGTON, WEST VIRGINIA.

MODE OF VENTILATING SEWERS AND TRAPS.

SPECIFICATION forming part of Letters Patent No. 252,548, dated January 17, 1882.

Application filed October 27, 1881. (No model.)

To all whom it may concern:

Be it known that I, JOHN G. TRENEAR, of Huntington, in the county of Cabell and State of West Virginia, have invented a new and 5 Improved Mode of Ventilating Sewers and Traps; and I do hereby declare that the following is a full, clear, and exact description of the same, reference being had to the accompanying drawing, forming part of this specification, in which the figure is a side elevation, 10 partly in section.

My invention relates to improvements in ventilating sewers and traps; and it consists in the peculiar construction and arrangement of the 15 parts, as hereinafter more fully set forth.

In the accompanying drawing, *a* represents a portion of a sewer-pipe, arranged in the usual manner below the bed of a street, and provided with the ordinary waste-water pipes, *b c*, communicating at their upper ends with sinks in a house, and opening into the sewer *a* at their lower ends in the usual manner, and provided near their lower ends with the ordinary bends or traps, *d e*, to prevent the ingress of sewer- 25 gas into the house.

h represents an air-pipe laid in the street, directly over the sewer and parallel therewith, or nearly so.

k *k* represent vertical pipes connecting the 30 air-pipe *h* with the sewer *a*. The mouth *l* of the air-pipe *h* communicates with the open air, and, if deemed necessary, an air-pump may be applied at the mouth of the air-pipe to increase the draft therein.

m represents a house provided with a chimney, *n*, having a furnace, *o*. One end of the

air-pipe *h* leads into the chimney, below the furnace, whereby the sewer-gas is consumed and a draft given to the air in the pipe *h*.

p represents an inclined pipe connecting the 40 air-pipe *h* with the trap *e*, to prevent the waste-pipe *c* from siphoning at the trap *e* when the waste-pipe *c* is full by the introduction of air from the air-pipe *h* through the inclined pipe *p*, and thus prevent the ingress of sewer-gas 45 into the house through the waste-pipe *c*.

q represents a bent or angular pipe leading from the sewer *a* to the trap *d* of the waste-pipe *b*. The function of the pipe *q* is to prevent the waste-pipe *b* from siphoning at the trap *d* by 50 furnishing air from the sewer when not convenient to attach the pipe *q* to the air-pipe *h*.

By this construction it will be seen that all gas will be removed from the sewer by passing through the vertical pipes *k* into the air-pipe 55 *h*, and thence to the furnace, where the gas is consumed. If any gas passes up through the lower end of the waste-pipe *c*, it will pass thence through the pipe *p* into the air-pipe *h*, and be carried thence to the furnace and consumed. 60

What I claim as my invention is—

The combination, with a sewer provided with the waste-pipe *c*, opening into the sewer, and having a trap, *e*, of the air-pipe *h*, opening into a chimney, *n*, below its furnace *o*, and pipes *k* 65 *p*, connecting the air-pipe *h* and sewer, whereby the sewer-gas is consumed, substantially as described.

JOHN G. TRENEAR.
